Attorney

UNITED STATES PATENT OFFICE.

LEVI JARVIS, OF CEDAR RAPIDS, NEBRASKA.

CORN HUSKER.

Application filed January 26, 1924. Serial No. 688,738.

To all whom it may concern:

Be it known that I, LEVI JARVIS, a citizen of the United States, residing at Cedar Rapids, in the county of Boone and State of

5 Nebraska, have invented a new and useful Corn Husker, of which the following is a specification.

The present invention has reference to corn husking devices, the primary object of 10 the invention being to provide a device of this character wherein the blades or hooks forming a part thereof may be adjusted with respect to each other to facilitate the use of the device.

15 Another important object of the invention is to provide a device of this character wherein the hooks or blades may be interchangeable, thereby adapting the device for various usages.

20 With the foregoing and other objects in view which will appear as the description proceeds, the invention resides in the combination and arrangement of parts and in the details of construction hereinafter described and claimed, it being understood 25 that changes in the precise embodiment of the invention herein disclosed, may be made within the scope of what is claimed, without departing from the spirit of the invention.

30 Referring to the drawing:

Figure 1 is a diagrammatical view disclosing a device constructed in accordance with the invention.

35 Figure 2 is a sectional view taken on line 2-2 of Figure 1.

Figure 3 is a perspective view of one of the hooks and disclosing a modified form thereof.

40 Referring to the drawing in detail, the reference character 5 designates a supporting strap to which the device, forming the subject matter of the present invention is secured.

45 Rivets 6 provide the securing means and extend through suitable openings formed in the body portion as clearly shown by Figure 1 of the drawing.

The body portion is indicated generally

50 by the reference character 7 and includes sections 8 and 9, pivotally connected at 10, so that one section may move with respect

to the adjacent section, while in use, it being understood that the device is strapped to the hand of the user, the body portion 55 resting in the palm of the hand.

Elongated openings 11 are formed in the sections and accommodate the bolts 12 that pass through suitable openings formed in the hook members or blades 13 to secure the 60 hook members to the body portion in a manner to permit of adjustment thereof with respect to each other and with respect to the body portion. Due to this construction, it will be obvious that two or more 65 hook members may be secured to the body portion, and may be adjustably secured so that they may be supported at angles with respect to each other should it be desired to support the same in this manner. 70

Operating on the inner ends of the bolts 12 are nuts 14 that hold the hook members against movement while in use, and when they have been adjusted to their proper positions. 75

Hand straps 15 are secured to the supporting member 5 and are designed to pass around the back of the hand of the user, where they may be secured to the hand of the user. 80

The strap 16 is secured at one end of the supporting strap 5 by means of the rivets 17, the last mentioned strap being designed to pass adjacent to the thumb of the user, the ends of the strap 16 being brought together on the back of the hand of the user, where they are secured. It will thus be seen that when the straps have been properly positioned, the device will be securely held against movement with respect to the 90 hand of the user to displace the device and prevent its efficient use. 85

In the modified form of the invention as illustrated by Figure 3 of the drawing, the blade includes a body portion 18 formed 95 with an elongated opening 19, one end thereof being turned inwardly and tapered to provide hook members 20 that may be forced into the husk to enable the same to be pulled from the ear of corn. 100

I claim:—

In a device of the character described a supporting strap, a supporting body having a longitudinally disposed slot secured to the

strap, a plurality of hook members, each of said hook members having an elongated opening, securing members adapted to pass through the slot of the body portion and 5 elongated openings of the hook members to secure the hook members to the body, whereby the hook members may be held in trans- verse relation to each other or in transverse or aligned relation. In testimony that I claim the foregoing 10 as my own, I have hereto affixed my signature.

LEVI JARVIS.
